HARRY D. GLIDDEN, OF WAVERLY, IOWA, ASSIGNOR OF ONE-THIRD TO A. J. SCHWARTZ
AND ONE-THIRD TO G. E. ROGGENSACK, BOTH OF WAVERLY, IOWA.

STEAM-ENGINE VALVE-GEAR.

1,324,661.

Specification of Letters Patent.

Patented Dec. 9, 1919.

Application filed April 12, 1918. Serial No. 228,188.

To all whom it may concern:

Be it known that I, HARRY D. GLIDDEN, a citizen of the United States, residing at Waverly, in the county of Bremer, State of Iowa, have invented a new and useful Steam-Engine Valve-Gear; and I do hereby declare the following to be a full, clear, and exact description of the invention, such as will enable others skilled in the art to which it appertains to make and use the same.

The present invention relates to a steam engine valve gear, and has for its object to provide a novel mechanism for transmitting motion from the crank of a drive wheel of a steam locomotive to the distributing valve which admits steam to the cylinder, said mechanism providing for an accurate timing or reversing of the action of the distributing valve and being at all times under the perfect control of the operator.

Further objects of the invention are to provide a device of this character which does not necessitate the use of complicated and delicate connections and bearings, and which is accordingly well adapted to withstand the rough usage to which such devices are subjected when installed upon railroad rolling stock, which can be used in connection with the conventional distributing valve mechanism employed upon locomotives, and which can be easily and quickly operated to reverse the action of the distributing valve at any time.

With these and other objects in view, the invention consists in certain novel combinations and arrangements of the parts as will more fully appear as the description proceeds, the novel features thereof being pointed out in the appended claim.

For a full understanding of the invention, reference is to be had to the following description and accompanying drawings, in which:

Figure 1 is a side elevation of a fragmentary portion of a locomotive, showing the valve gear mechanism mounted thereon.

Fig. 2 is a top plan view thereof.

Fig. 3 is a transverse sectional view.

Fig. 4 is a vertical longitudinal sectional view through the reversing shaft and radius shaft, showing a portion of the locomotive frame upon which the reversing shaft is mounted.

Corresponding and like parts are referred to in the following description and indi-

cated in all the views of the drawings by the same reference characters.

Referring to the drawings, which illustrate one embodiment of the invention, the numerals 1 designate a pair of conventional locomotive drive wheels which are mounted upon an axle 2, portions of the side bars of the locomotive frame being indicated at 3. The main crank 4 of each of the drive wheels is provided with a rigidly connected auxiliary crank 5 which stands 90° forward of the main crank. The usual pitman 6 is connected to the main crank 4, while an auxiliary pitman 7 is connected at one end thereof to a wrist pin 8 at the end of the auxiliary crank 5. It will be noted that the annular path of the wrist pin 8, which is indicated by the dotted lines 9, is smaller than the annular path of the main crank 4, as indicated by the dotted lines 10. The usual cross head 75 guide bars are shown at 11, said bars being secured at their ends to a yoke 12 which is provided at its upper portion with a bracket 13 upon which a bell crank lever 14 is pivotally mounted at 15.

One arm of the bell crank lever 14 is pivotally connected at 16 to the valve stem 17 of a conventional distributing valve. The other arm of the bell crank lever 14 is loosely connected by a downwardly extending link 17 to the free end of the auxiliary pitman 7. The two auxiliary pitmen 7 are pivotally connected at points spaced from the free ends thereof, by means of suitable pins 18, to the lower ends of radius hangers 19. The upper ends of the hangers 19 are loose upon a radius shaft 20 which extends transversely across the locomotive and is supported by radius arms 21. The upper ends of these radius arms 21 are provided with sleeves 22 which receive the radius shaft, set screws 23 being employed to obtain a rigid connection between the said members. The lower ends of the radius arms 21 are provided with sleeves 24 which are keyed upon a reversing shaft 25, said shaft extending transversely across the frame of the locomotive and having the extremities thereof journaled in bearings 26 which are suitably secured to the side bars 3 of the locomotive frame.

The radius shaft 20 is connected by a link 27 to a reversing lever 28 which is located at some convenient point upon the locomotive. It will be obvious that by manipu-

lating this lever 28 the radius shaft 20 can be moved back and forth in the arc of a circle about the reversing shaft 25 as a center. This movement of the radius shaft is indicated by dotted lines on Fig. 1. When the engine is in operation it will be apparent that the auxiliary pitmen 7 will oscillate about the pivot pins 18 at the lower ends of the radius hangers 19, and that the said pins 18 will also oscillate back and forth about the radius shaft 20 as a center. When the positioning of this radius shaft 20 is shifted, the arcuate path of the pivot pin is changed, and in this manner the operation of the steam distributing valve can be timed in the desired manner relative to the movements of the drive wheel. A full movement of the reversing lever 28 will operate to reverse the action of the distributing valve and reverse the engine. This valve gear is free from delicate and complicated parts and has nothing to break or get out of adjustment, even when subjected to rough usage.

Having thus described the invention, what I claim as new and desire to secure by Letters Patent, is:—

In a valve gear for railway locomotives, the combination with the main frame, pitman and crank shaft, of an auxiliary crank set at an angle to the main crank, an aux-

iliary pitman having one end thereof pivotally connected to the auxiliary crank, a lever arranged above the main pitman and operatively connected to the steam distributing valve, an upright link pivotally connecting the said lever to the free end of the auxiliary pitman, bearings at opposite sides of the locomotive frame, a reversing shaft extending transversely across the locomotive frame and journaled in the bearings, a transversely disposed radius shaft arranged above the reversing shaft and extending across the locomotive frame in a parallel relation to the radius shaft, radius arms pivotally connecting the reversing shaft and radius shaft and supporting the latter, an upright radius hanger pivotally connecting the radius shaft to an intermediate portion of the auxiliary pitman, and a reversing lever operatively connected to the radius shaft for swinging the same about the reversing shaft as a center to regulate the operation of the steam distributing valve.

In testimony whereof I have signed my name to this specification in the presence of two subscribing witnesses.

HARRY D. GLIDDEN.
